PROCESS AND APPARATUS FOR HANDLING MATERIALS

Robert A. Gift, Jr., Trenton, N. J., assignor to Filatex Corporation, New York, N. Y., a corporation of New Jersey

Application May 6, 1940, Serial No. 333,502

16 Claims. (Cl. 242—43)

The present invention relates to the winding of filaments. More particularly, it relates to the winding of filaments onto forms under constant tension throughout the winding and in such manner as to produce a uniformly shaped body of wound material.

In the winding of bobbins, spools, cones and the like heretofore, particularly with filaments having appreciable elasticity, such as elastic yarn comprising a rubber core provided with a textile covering, and the like, it has been impossible to maintain the filaments under constant tension throughout the winding operation. This has been due in part to the fact that in the majority of winding methods and apparatus heretofore employed, the shaft which supports the winding form is driven at a uniform speed with the result that the surface speed of the winding on the form increases as the diameter of the winding increases, thereby placing the portion of the filament towards the outside of the winding under a much greater tension than the portion of the filament nearer the winding form. Efforts have been made to drive the winding apparatus so that the winding accreting on the form will have a substantially constant surface speed, but all such methods heretofore employed have not been capable of use in forming peculiarly shaped wound bodies such, for example, as the winding commonly known as a "pineapple cone," in which the top and bottom edges of the conical winding are slanted towards each other away from the axis of the winding. Furthermore, it has been impossible to rotate a wound body at uniform surface speed by the use of facilities heretofore available since the surface of a wound body becomes irregular and thereby provides an irregular contacting surface for co-operation with a friction roller or the like. Also, the friction set up between filament guides heretofore available and the filament being wound has caused the filament to have an irregular tension throughout the winding operation.

It is a general object of the present invention to provide a process and apparatus for winding filaments, such, for example, as elastic rubber yarns or bare rubber cores, upon forms under substantially uniform tension.

It is another object of the present invention to provide a wound body in which the filament is under substantially uniform tension throughout.

It is still another object of the present invention to provide a substantially uniformly-shaped wound body.

It is a further object of the present invention

to provide a process and apparatus for feeding and guiding filaments to winding forms under substantially uniform tension.

It is also a further object of the present invention to provide a process and apparatus for producing wound bodies having a non-uniform diameter throughout their length such as those known commercially as "pineapple cones," in which the filament is under substantially uniform tension throughout the wound body.

It is still a further object of the present invention to provide a process and apparatus for winding filaments into wound bodies in which the filaments are under sufficient tension to cause the wound bodies to be stable during handling and shipping and at the same time will readily release from the bodies during usage without hanging.

Other objects and advantages will be apparent from the following description of the invention.

The process of the present invention in general comprises supporting and rotating a winding form by a zone of force exerted by frictionally contacting the winding form and subsequently 25 the surface of the wound body which builds up on the form with a rotating member and traversing the rotating member backwards and forwards along the surface of the wound body while it is rotating and, if desired, decreasing the amplitude 30 of traverse of the rotating member in each direction in accordance with the increase in diameter of the wound body to thereby provide a wound body of desired shape, such, for example, as a "pineapple cone."

35 The apparatus of the present invention comprises a combination of elements capable of winding filamentary material into a wound body of desired shape and in which the filamentary material is under substantially uniform tension.

40 The invention accordingly comprises the several steps and the relation of one or more of such steps with respect to each of the others, and the apparatus embodying features of construction, combinations of elements and arrangements 45 of parts which are adapted to effect such steps, all as exemplified in the following detailed disclosure, and the scope of the invention will be indicated in the claims.

For a more detailed description of the present invention reference should be made to the drawings wherein:

Fig. 1 is a front elevational view of one form of apparatus constructed in accordance with the present invention and capable of use in the practice of the method of the present invention, cer-

tain of the elements of the apparatus being omitted for the sake of clarity;

Fig. 2 is a plan view of the apparatus illustrated by Fig. 1;

Fig. 3 is a side elevational view of the apparatus of the present invention, partly in section, taken along the plane indicated by the line 3—3 of Fig. 1 and looking in the direction of the arrows;

Fig. 4 is a detailed view of the friction driving member of the apparatus partly broken away for the sake of clarity and executed upon an enlarged scale, and

Fig. 5 is a detailed sectional view of a portion of the traversing mechanism executed on an enlarged scale and taken substantially on the plane indicated by line 5—5 of Fig. 3 and looking in the direction of the arrows.

For the purpose of explanation the present invention will be described in connection with the winding of elastic rubber yarns or bare rubber cores upon conically-shaped winding forms, but it is to be understood that the invention may be utilized in connection with the winding of any filamentary material, such as thread, wire, rope, tape and the like upon a cylindrical or any other shape of winding form desired. Elastic yarn, of the type previously described and the bare elastic core have been selected for use in the description of the present invention because these materials are the most difficult to uniformly wind upon a form of any of the known types of filamentary material. Elastic filaments of this type will undergo large stretch upon application of light tensioning forces, and consequently will vary greatly in tension throughout the wound body if the winding tension is not maintained absolutely uniform. Variation in tension throughout a wound body of elastic yarn is highly detrimental to the efficient use of such yarn since the variation in tension is carried forward with the yarn into the finished article, and in some instances is actually magnified, with the result that finished articles such as knitted or woven goods will pucker or otherwise be distorted after completion because of the irregularity in the tension of the elastic yarn or the bare elastic core used in the fabrication of the articles.

Structure of the apparatus

The apparatus illustrated in Fig. 1 comprises an arbor 10 carried by an arm 12 which is mounted for rotation with a shaft 14 suitably journaled for rotation in an upright 16. The arbor 10 is mounted so as to project downwardly away from the arm 12 at an angle to the horizontal and is provided with a conventional cone winding form holder 18 shown in dotted lines in Fig. 1. The holder 18 receives and frictionally grips a conventional cardboard cone winding form 20, and the angle which the arbor 10 makes with the horizontal is selected so that the lower face of the conical form 20 is substantially horizontal when the cone 20 is in the initial winding position without any filamentary material wound thereon.

A rotatable and reciprocable friction driving member 22 is carried by a shaft 24 which is provided with a spline 26 which receives a key 28 disposed within a keyway 30 in the bore 32 of the friction driving member 22. The member 22 is thereby rotated by rotation of the shaft 24 which may be driven by a pulley 34 which is connected with pulley 36 carried by a cam shaft 38 by means of a belt connector 40. The spline connection between the shaft 24 and the mem-

ber 22 enables the latter to be reciprocated on the shaft 24 while the shaft and member are rotating.

The apparatus for reciprocating the member 22 comprises a yoke arm 42 provided on its upper end with furcations 44 which are received within an annular groove 46 cut in the boss 48 formed integrally with or suitably attached to the friction driving member 22.

The yoke arm 42 has ears 50 formed on the side thereof which are suitably shaped to engage with guide rods 52 carried by suitable frame members 54 which rotatably support the spline shaft 24. The yoke arm 42 is provided with a foot 56 which has a blind slot 58 formed therein. A stud 60 is carried by a slide 62 and received within the slot 58.

The slide 62 is received within a depression 64 formed in an arm 66 fastened to a segmental gear 68 by means of pins or the like 70. The gear 68 is carried by a stud shaft 71 journaled for oscillation in a projection 72 of a plate 74 supported by a standard 75. Oscillation of the arm 66 causes the yoke arm 42 to be reciprocated on the guide rods 52 and thereby reciprocate the friction driving member 22 on the spline shaft 24.

The segmental gear 68 is oscillated by means of a rack 76 received within a way 78 formed within the plate 74. The bottom of the way 78 is provided with a slot 80 through which a cam follower 82 mounted on the rack 76 projects. The cam follower 82 is received within a cam groove 84 formed in a cam 86 rotated by the shaft 38. The cam shaft 38 is driven by means of a pulley 88 carried thereby and a pulley 90 carried by a line shaft 92 suitably supported by bearing standards 94. The pulleys 88 and 90 are connected by a belt 96. Rotation of the cam 86 causes the follower 82 and the rack 76 to reciprocate and, in turn, oscillate the segmental gear 68.

Since the rotatably mounted conically-shaped form 20 initially rests upon the friction driving member 22, it follows that rotation of the member 22 causes rotation of the form, and a filament 98 passed through a pigtail guide or the like 100 carried by yoke arm 42 and then passed into an annular groove 102 in the friction driving member 22 and then suitably fastened around the form 20 is thereby wound upon the form and caused to substantially cover the same as the member 22 is traversed backwards and forwards by the traversing mechanism previously described.

As a wound body builds up on the form, the frictional winding member 22 will contact with the surface of the body and drive the same at a constant surface speed so as to feed the elastic yarn upon the wound body under uniform tension. The wound body 104 so formed will gradually increase in diameter and move the arbor 10 upwardly to thereby rotate the arm 12 and the shaft 14. The shaft 14 has an arm 106 connected for movement therewith. The other end of the arm 106 is formed into a clevis 108 and a link 110 is pivotally connected within the clevis in any desired manner. The lower end of the link 110 is likewise pivotally connected to the end of an arm 112 mounted for rotation with a shaft 114 suitably journaled in the upright 16 and in an arm 116 carried by a suitable standard 118. A gear 120 is mounted on the end of shaft 114 opposite from the end that carries the arm

112 and is suitably connected to the shaft 114 for rotation therewith.

The gear 120 meshes with a rack 122 slidably mounted for vertical movement within arms 124 and 126 carried by the standard 118. The rack 122 is connected at its lower end with a rod 128 by means of a conventional swivel connection 130 which causes the rack 122 and rod 128 to move together vertically, but enables the rod 128 to rotate axially relative to the rack 122. A cam 132 is rigidly mounted on the lower end of rod 128 and is received within an upwardly-extending housing 134 carried by the arm 66 of the traversing mechanism. The cam surface 135 of the cam 132 coacts with a cam surface 136 formed on the end of the slide 62. The slide 62 is urged towards cam 132 so as to maintain the cam surface 135 of the cam 132 in contact with the cam surface 136 of the slide 62 by means of a spring 138 disposed within the recess 64 and operative between the end 140 of the slide 62 and the interior face 142 of the recess 64. Upward movement of the rack 122 causes upward movement of the cam 132 with resultant movement of the slide 62 towards the cam 132 under the force exerted by the spring 138, with the result that the stud 60 is moved towards the outer end of the blind slot 58 to thereby decrease the amplitude of reciprocatory movement of the yoke arm 42. Oscillation of the arm 66 causes the rod 128 to oscillate simultaneously but this oscillation is not imparted to the rack 122 because of the swivel connection 130.

Filamentary material to be wound upon the winding form 20 may be supplied from a reel, such as a swift 144 carried by a shaft 146 which is suitably mounted for rotation in open top bearings 148 in standards 150. The shaft 146 is suitably driven as by means of a pulley 152 mounted for rotation therewith which is driven from a pulley 154 mounted for rotation on shaft 92 by means of a belt or the like 156. The swift 144 may, if desired, be of the collapsible type well known in the art and may have a skein of filamentary material 158 applied thereto in a well known manner.

The filament 98 is led from the skein 158 and passed between a pair of positively driven feed rollers 160. The lower roller of the pair is mounted for rotation with a shaft 162 suitably journaled for rotation in standards 164, and may be driven by means of a pulley 166 mounted for rotation therewith from a pulley 168 mounted for rotation with the shaft 92 by means of a belt 170. The upper roller of the pair of rollers 160 is mounted upon a stub shaft 172 which is mounted for rotation in open top bearings 174 formed in the standards 164. The speeds of rotation of the feed rollers 160 and the friction driving member 22 are proportioned so that the surface speeds of these rotating elements are such that a loop 176 initially formed in the filament 98 between the feed rollers 160 and the pigtail guide 100 is substantially maintained during the winding operation.

Operation of the apparatus

Elastic filamentary material 98 is led from the skein 158 carried by the swift 144 and is passed between the feed rollers 160 and is then permitted to fall into a loop 176 and passed through the pigtail 100. It is then passed into the annular groove 102 of the friction drive member 22 and is wrapped several times around the form 20 to fasten it to the form.

The machine is then started in operation as by energizing the prime mover (not shown) which drives shaft 92 or by operation of a conventional clutch or the like (not shown) through 5 which the shaft 92 is driven. As the swift 144 rotates, elastic filamentary material 98 is fed therefrom and passed between the positively driven feed rollers 160. As the elastic material passes from between the feed rollers 160, substantially all tension existing within the material is relieved and the filamentary material assumes a relaxed state within the loop 176 from which it passes through the pigtail 100 or any desired type of tensioning device onto the winding form 20 through the annular guide groove 102 of the member 22.

During rotation of the machine, the cam 86 rotates and causes follower member 82 to reciprocate in the slot 80 and, in turn, causes reciprocation of the rack 76 which coacts with the gear 68 to oscillate the latter and, in turn, oscillate the arm 66. The pin 69 operating in slot 58 causes the yoke arm 42 to be reciprocated and through the medium of the yoke formed by furcations 44 causes the friction drive member 22 to be traversed backwards and forwards along the winding form 20. The cam groove 84 of the cam 86 is suitably shaped in well known manner so as to cause the speed of traversing movement of the friction driving member 22 to be greater between the mid point of the winding form 20 and the smaller end of the form than between the mid point of the winding form and the larger end so as to prevent the filamentary material 98 from building up to a greater extent at the small end of the winding form 20 than at the larger end due to differences in diameter along the conically-shaped winding form 20.

40 The filamentary material 98 is thus uniformly wound upon the winding form 20 to form a compact and uniformly shaped wound body 104 in which the filamentary material 98 exists under substantially uniform tension due to the fact 45 that the filament in the loop 176 is untensioned and the filament is substantially uniformly tensioned as it passes through the pigtail 100 or other desired type of tensioning device prior to being laid upon the winding form 20. If desired, any suitable tensioning device such as a glass 50 rod or rollers positively driven from the shaft 24 may be used in place of or in addition to the pigtail guide 100 to impart any amount of uniform tension desired to the filamentary material as it is being wound.

55 As the wound body 104 increases in diameter due to the filamentary material 98 accreting thereon, the arbor 10 is moved upwardly and rotates the arm 12 which, in turn, causes the shaft 14 to rotate the arm 106 upwardly so that the arm 112 is rotated upwardly or in clockwise direction, as viewed in Fig. 3, by means of the link 110. Clockwise rotation of the arm 112 rotates the gear 120 by means of the shaft 114 and the rack 122 is thereby moved upwardly to move the cam 132 upwardly so as to permit the slide 62 to move to the right as viewed in Figs. 3 and 5 and thus move the stud 60 towards the outer end of the slot 58 in the foot 56 of the yoke arm 42. This 60 reduces the effective radius of oscillation of the stud 60 during oscillation of the arm 66 and thereby progressively reduces the amplitude of reciprocation of the yoke arm 42 which causes the amplitude of traverse of the friction driving member 22 to be likewise reduced in both direc-

tions. This action causes the area of the wound body traversed to be reduced progressively as the body increases in diameter, with the result that the ends of the wound body slant towards each other away from the axis of the winding form to produce the surfaces 180 and 182 at the ends of the body and thereby form the well known "pineapple" type of cone winding.

The combined rolling and sliding friction between the surface of the friction driving member 22 and the surface of the wound body causes the surface to be continuously smoothed during the winding operation and thereby form an exceptionally smooth winding on the body 104 in which the elastic filamentary material is uniformly tensioned throughout the body, is also sufficiently tensioned to cause the body to be able to retain its shape during handling and shipping, and at the same time permits the elastic filamentary material to be readily released from the wound body without sticking or hanging so as to eliminate jerky feeding action when the body is being used to supply elastic yarn or the like to various fabricating machines, such as knitting machines, looms, braiders and the like. This enables elastic yarn to be rapidly and economically fabricated so as to produce finished textile articles which are free from pockers, streaks and other disfigurements common to textile articles heretofore manufactured from elastic yarns.

Since certain changes in carrying out the above process and in the construction set forth, which embody the invention, may be made without departing from its scope, it is intended that all matter contained in the above description or shown in the accompanying drawings shall be interpreted as illustrative and not in a limiting sense.

The invention having been described, what is claimed is:

1. A filament-winding apparatus, comprising means for rotatably mounting a winding form, reciprocable means for rotating said winding form through frictional contact with the surface of the wound body which builds up thereon, means for rotating and reciprocating the reciprocable means, means for supplying filamentary material in substantially relaxed state, means for uniformly tensioning the relaxed filamentary material, and means for feeding the tensioned filamentary material to the winding form.

2. A filament-winding apparatus, comprising means for rotatably mounting a winding form, reciprocable means for supporting and rotating said form through frictional contact with the surface of the form and subsequently with the surface of the wound body which builds up thereon, means for reciprocating and rotating said reciprocable means, means for feeding filamentary material to the said winding form between said form and the reciprocable means, and means for progressively decreasing the amplitude of reciprocation of said reciprocable means as the diameter of the wound body increases.

3. A filament-winding apparatus, comprising means for rotatably mounting a winding form, reciprocable means for supporting and rotating said form through frictional contact with said form and subsequently with the surface of the wound body which builds up thereon, means for rotating and reciprocating said reciprocable means, filament supply means, means for feeding a filament from said supply means at a substantially constant speed, means for guiding said filament to the winding form between the wind-

ing form and the reciprocable means, the speeds of rotation of said reciprocable member and filament feeding means being proportioned so that a loop initially formed in the filament between the feeding means and the reciprocable member will be substantially maintained, and means actuated in unison with the increase in diameter of the wound body to progressively decrease the amplitude of reciprocation of the reciprocable member.

4. A filament-winding apparatus, comprising a substantially cylindrically-shaped member mounted for rotation and reciprocation and provided with an annular groove therein, means for 15 rotatably mounting a winding form in position to be supported and rotated by said member through frictional contact between the surface of the winding form and subsequently between the surface of the wound-body which builds up thereon and said member, means for rotating and reciprocating said member, means for feeding filamentary material to said winding form through the groove of said member, and means actuated by the raising of the winding form 20 mounting means as the wound body increases in diameter to progressively decrease the amplitude of reciprocation of said member.

5. A filament-winding apparatus comprising a movable support, a winding-form holder rotatably carried thereby, a rotatably mounted shaft, means for driving said shaft, a cylindrically-shaped member carried by said shaft in position to support and rotate a winding-form when the latter is in position on the winding-form holder to receive filamentary material from any suitable supply source, means for connecting said cylindrical member and said shaft for rotation together and for relative reciprocating movement, and means for reciprocating said cylindrical member along said shaft as said shaft rotates to cause said cylindrical member to rotate said winding-form and any winding which builds up thereon while reciprocating longitudinally of the form.

6. A filament winding apparatus comprising a movable support, a winding-form holder rotatably carried thereby, a rotatably mounted shaft, means for driving said shaft, a cylindrically-shaped member carried by said shaft in position to support and rotate a winding-form when the latter is in position on the winding-form holder to receive filamentary material from any suitable supply source, means for connecting said cylindrical member and said shaft for rotation together and for relative reciprocating movement, means for reciprocating said cylindrical member along said shaft as said shaft rotates to cause said cylindrical member to rotate said winding-form and any winding which builds up thereon while reciprocating longitudinally of the form, and means for progressively decreasing the amplitude of reciprocation of said cylindrical member as a winding builds up on said winding-form.

7. A filament winding apparatus comprising a movable support, a winding-form holder rotatably carried thereby, a rotatably mounted shaft, means for driving said shaft, a cylindrically-shaped member carried by said shaft in position to support and rotate a winding-form when the latter is in position on the winding-form holder to receive filamentary material from any suitable supply source, means for connecting said cylindrical member and said shaft for rotation together and for relative reciprocating movement,

means for reciprocating said cylindrical member along said shaft as said shaft rotates to cause said cylindrical member to rotate said winding-form and any winding which builds up thereon while reciprocating longitudinally of the form, and means operated by movement of said support due to a winding building up on said winding-form to progressively decrease the amplitude of reciprocation of said cylindrical member.

8. A filament winding apparatus comprising a movable support, a winding-form holder rotatably carried thereby, a rotatably mounted shaft, means for driving said shaft, a cylindrical member carried by said shaft in position to support and rotate a winding-form when the latter is in position on the winding-form holder to receive filamentary material from any suitable supply source, means for connecting said member and shaft for rotation together and for relative reciprocating movement, rotating driving means, adjustable motion translation means connecting said driving means and said cylindrical member and translating the rotative movement of the driving means to reciprocative movement for reciprocating the cylindrical member longitudinally of said winding-form, and means operated by movement of said support caused by a winding building up on said form to adjust said motion translating means to progressively reduce the amplitude of reciprocation of said cylindrical member as said winding increases in size.

9. In a process of winding filaments, the steps comprising feeding a filament to a rotatable form, exerting a zone of force against the winding which builds up on the form to simultaneously support and rotate the winding, the said zone of force always including the point at which the filament is fed to the winding, and traversing said zone and said point backwards and forwards along the winding during the rotation thereof while preventing relative movement between said point and the effective portion of said zone.

10. In a process of winding filaments, the steps comprising feeding a filament to a rotatable form, exerting force against the winding which builds up on the form to simultaneously support and rotate the winding, the said force always being exerted over an area which includes the point at which the filament is fed to the winding, traversing the area of application of said force backwards and forwards along the winding during the rotation thereof, and progressively decreasing the amplitude of the traverse in each direction as the winding on the form increases in diameter.

11. In a process of winding filaments, the steps comprising feeding a filament to a rotatable form, exerting a zone of force against the winding which builds up on the form to simultaneously support and rotate the winding, traversing any given point in the zone of force backwards and forwards along the axis of the winding during the rotation thereof, and progressively decreasing the

amplitude of the traverse in each direction as the winding which builds up on the form increases in diameter.

12. In a process of winding filaments, the steps comprising feeding a filament to a rotatable form, causing the filament to assume a substantially relaxed state before it is fed to said form, exerting a zone of force against the winding which builds up on the form to simultaneously support and rotate the winding, and traversing the zone of force backwards and forwards along the axis of the winding during the rotation thereof.

13. In a process of winding filaments, the steps comprising feeding a filament to a rotatable form, causing the filament to assume a substantially untensioned state before it is fed to said form, exerting a zone of force against the winding which builds up thereon to simultaneously support and rotate the winding, the said zone of force always including the point at which the filament is fed to the winding, and traversing said zone of force backwards and forwards along the axis of the winding during the rotation thereof.

14. In a process of winding filaments, the steps comprising feeding a filament to a rotatable form, causing the filament to assume a substantially relaxed state before it is fed to said form, exerting a zone of force against the winding which builds up thereof to simultaneously support and rotate the winding, the said zone of force always including the point at which the filament is fed to the winding, traversing said zone of force backwards and forwards along the winding during the rotation thereof, and progressively decreasing the amplitude of the traverse in each direction as the winding which builds up on said form increases in diameter.

15. A filament-winding apparatus, comprising a substantially cylindrically-shaped member mounted for rotation and reciprocation and provided with an annular groove therein, means for rotatably mounting a winding form in position to be supported and rotated by said member through frictional contact between the surface of the winding form and subsequently between the surface of the wound body which builds up thereon and said member, means for rotating and reciprocating said member, and means for feeding filamentary material to said winding form through the groove of said member.

16. A filament-winding apparatus comprising means for rotatably mounting a winding form, rotatable reciprocable means for supporting and rotating said form through frictional contact with said form and subsequently with the surface of the wound body which builds up thereon, means for rotating and reciprocating said reciprocable means, and means carried directly by said rotatable and reciprocable means for feeding a filament from a suitable supply source to said winding form.

ROBERT A. GIFT, JR.
